TOBACCO FEEDING APPARATUS

Walter Everett Molins, deceased, late of Deptford, London, England, by Harold Bernardo Molins, Deptford, London, and Moses Hyman Isaacs, London, England, executors, and Sydney Alfred Nichols, Deptford, London, England, assignors to Molins Machine Company, Limited, Deptford, London, England

Application February 10, 1936, Serial No. 63,256
In Great Britain March 8, 1935

10 Claims. (Cl. 131—39)

This invention is for improvements in or relating to tobacco feeding apparatus, and refers to a tobacco feeding apparatus of the kind in which tobacco in a hopper is fed from a mass of tobacco contained therein by a feeding element to a carded element and in which the short tobacco which falls between the feeding element and the carded element or any two elements in the hopper is collected. Such an apparatus is referred to hereinafter as "apparatus of the kind described".

According to the present invention there is provided in or for apparatus of the kind described the combination of a conveyor to collect or receive short tobacco, means co-operating with the conveyor to maintain the tobacco collected thereby or received thereon substantially in the original arrangement or formation in which it is collected by or received on the conveyor until it is delivered by or from the conveyor and a support which is movable in timed relationship with the conveyor, said support being arranged to convey the tobacco to a position at which it is removed from the support and deflected towards the place to which it is desired to deliver the tobacco (e. g., into the hopper or on to a travelling surface).

The conveyor may comprise a relatively smooth travelling surface (e. g., an endless band) and the means co-operating therewith also may comprise a travelling surface. The means co-operating with the conveyor may comprise a continuation of the support and in such a case the travelling surfaces comprising the conveyor and the support respectively are movable in substantially L paths, the two L's being relatively inverted with the upright limbs co-operating to hold the tobacco therebetween and convey it in the original arrangement or formation from the base of one L to the base of the other L.

A guide element or guide elements may be provided to maintain the co-operating portions of the bands in close proximity with one another, and such element or elements may comprise a member or members between or through which the co-operating portions of the bands pass. The tobacco may be removed from the support by a sweeping device (e. g., a rotatable worm or spiral brush).

By way of example one construction will now be described with reference to the accompanying drawings, in which:—

Figure 1 is a sectional end elevation of tobacco feeding mechanism, showing the invention applied thereto.

Figure 2 is a section on line 2—2, Figure 1.

Figure 3 is a section on line 3—3, Figure 2.

Figure 4 shows a modified form of the invention.

Like references refer to like parts throughout the specification and drawings.

Referring to Figures 1 and 2, a mass of tobacco is contained in a hopper 5 and tobacco from the mass is fed by a feed roller 6, shown in the drawings as a carded roller, to a carded roller 10 hereinafter referred to as a combing roller 1. The combing roller carries the tobacco beneath a brushing roller 8 arranged to sweep back surplus tobacco from the surface of the combing roller. After passing the brushing roller, the tobacco on the surface of the combing roller 7 is carried to a point at which it is picked from the surface of the combing roller by a fast rotating picking roller 9, which showers the tobacco on to the surface of a distributor element 10, which is shown in the drawings as a distributor roller, but may, if desired, comprise an endless band. The tobacco is picked from the surface of the distributor roller 10 by a fast moving picker roller 11 and is showered on to the moving surface 25 in a trough 13 of a continuous rod cigarette making machine.

Beneath the feeding roller 6 and combing roller 7 there is arranged an endless band 14, and guiding elements 15 and 16 are provided to guide on to the endless band short particles of tobacco which fall between the rollers 6 and 7 and/or the rollers 7 and 10 during the feeding operation. The band 14 is passed around guide rollers in a manner such that it moves through substantially an L shaped path, as can be seen from Figure 2.

Above the floor there is arranged a further endless band 17 which is arranged as a support for the short tobacco which has been collected by the band 14 and is to be deposited into the hopper 5. The band 17 is passed around suitable guiding rollers so that it follows a substantially L shaped path, but in this case the L is, as will be seen from Figure 2, an inverted L. The portions 14A and 17A of the bands 14 and 17 respectively which are the upright limbs of the L's move in a substantially vertical plane in the construction shown. These upright limbs of the L's are arranged to co-operate with each other to grip the tobacco collected by the band 14 and to convey it upwardly so that the collected tobacco is delivered on to the supporting surface of the band 17. By this means the short tobacco which is collected by or received on the base of 55

the L formed by the band 14 is delivered to the supporting surface which is constituted by the base of the L formed by the band 17 so that it is maintained substantially in the arrangement in 5 which it was collected upon the band 14.

The co-operating portions 14A and 17A of the bands 14 and 17 respectively are passed through a guide 18, which guide is, as can be seen from Figure 3, of C cross-section.

10 By passing the bands through the guide member, the edges of the bands are held together and the guides, together with the tension between the two bands, maintain the tobacco in position between the bands until it is delivered to the supporting surface of the band 17. If desired, instead of the guide member being of C cross-section, two guide members of U cross-section may be provided, each of the members being disposed so that the edge portions of the bands pass 15 through the U guides.

15 Above the surface of the endless band 17, there is arranged a sweeping element 19, shown in the drawings as a worm, and the member 19 sweeps over the surface of the endless band 17 and deposits the tobacco on to the surface of the roller 7, the tobacco being guided on to the roller 7 by 20 guide plates 20 and 22. The plate 22 is arranged so that when a roll of tobacco is in the junction formed by the co-operating surfaces of the rollers 7 and 8, such for example, as a roll such as that 25 shown and described in British patent specification No. 385,210, the short tobacco is directed on to the surface of the roller 7 so that it is deposited on to the surface of the tobacco on the roller 7, and is thus passed beneath the tobacco roll. In such cases when additional tobacco is taken 30 by the roller 7 from the tobacco roll, the short tobacco is sandwiched between the tobacco taken from the roll of the tobacco carried by the roller 7. By forming the sweeping elements as shown 35 in the drawings, it will be seen that the supporting surface of the band 17 is cleaned along its length by reason of the shape of the sweeping element. If desired, instead of the worm shown 40 in the drawings, the sweeping element may comprise a brush which is formed about the spindle 21 of the rotating sweep in a manner such that it forms about the spindle a spiral similar to that 45 formed by the worm 19.

50 In the construction illustrated in the drawings, the worm 19 deflects the tobacco from the supporting surface of the band 17 in a manner such that it is thrown on to the guide plates 20 at an angle of approximately 45°, and this action tends 55 to throw the tobacco towards the right hand side of the hopper when viewed in Figure 2. This result is brought about due to the fact that the support imparts to the tobacco a force in the direction of movement of the support, whilst the 60 action of the worm 19 tends to impart a force in a direction inclined to the first force. The resultant of these two forces is such that the tobacco is discharged from the support at substantially 45° as above set forth.

65 If it is desired that the tobacco should be deposited more over the central portion of the roller 7, this may be done by rotating the worm 19 so that it makes two revolutions whilst cleaning a 70 length of the supporting surface, equal to the length of the worm. It follows from the description just given that by suitably arranging the relative speeds of the conveyors 14 and 17 on the one hand and the sweeping element on the other hand, the tobacco removed by the sweeping 75 element from the supporting surface can be ar-

ranged so that it is delivered where desired on the surface of the roller 7.

If it is not desired to increase the speed of the worm 19, the same effect may be obtained by inclining the vertical portions 14A and 17A shown in Figure 2, so that the portion 14A forms an obtuse angle with the horizontal portion of the band 14, and the portion 17A forms an acute angle with the horizontal portion of the supporting band 17. The rollers around which the supporting surface 17 pass would accordingly be moved to the left of Figure 2 so that the whole of the supporting surface is moved in that direction, and the sweeping element 19 will be correspondingly moved. In this manner the 15 sweeping element may be driven at a speed such that during one revolution of the sweeping element it completely cleans the supporting surface and the tobacco thus removed from the supporting surface is distributed over the desired portion 20 of the roller 7.

25 Brushes 23 are provided if it is considered desirable to clean the surface of the support 17. The brushes 23 remove portions of tobacco which may be clinging to the surface, after the bulk of the tobacco has been removed by the sweeping device 19 and the tobacco removed by the brushes 23 falls into the hopper.

30 Similarly, brushes 24 can be provided to remove tobacco which adheres to the conveyor 14, the tobacco removed by these brushes falling on to the support 17.

35 Referring to the modified construction shown in Figure 4, the portions 14A and 17A of the bands 14 and 17 respectively are passed over guide rollers 22 which cause the co-operating portions 14A and 17A of the bands to follow a substantially zigzag path. In this case the co-operating upright limbs of the L's are not rectilinear, and it will be appreciated that the bands 40 may be suitably controlled to follow any desired path so long as the bases of the two L's are arranged to form surfaces, one upon which the short tobacco is collected or otherwise received and the other from which it is removed whilst 45 the co-operating upright limbs of the L's maintain control of the tobacco during its conveyance. Where in the claims the term L is used to describe the path of the conveyor and/or supporting surface, it is to be understood that the term includes 50 all the constructions described herein, such for example, as the construction shown in Figures 2 and 4 of the drawings, and the construction in which the co-operating upright limbs of the L's form obtuse and acute angles respectively with 55 the bases of the L's, the limbs of the L's need not be straight, but can follow any desired path as aforesaid.

60 In the construction just described, it is not necessary to employ guides such as the guide 18, although if desired, U shaped guides may be provided in conjunction with the guide rollers 22. The guide roller 22 may be adjustable in order 65 suitably to tension the bands. If desired, the guide rollers may be of convex or concave configuration the better to retain the tobacco between the bands.

70 It will be seen that by means of the present invention short tobacco is returned to the hopper at the same rate as that at which it is collected, 70 since no matter how little or how much short tobacco falls at a given moment, all of that tobacco which goes between the bands is conveyed as it arrives by being gripped between the conveyor surfaces and is thereby returned to the 75

hopper. The bands 14 and 17 may be moved faster or slower according to the amount of short tobacco falling, but the bands move at the same speed in relation to one another.

5 When the tobacco feeding apparatus is used with a cigarette making machine the linear speed of the bands 14 and 17 may be the same as that of the cigarette paper web, so that the percentage loss in tobacco in the continuous cigarette 10 rod which would result due to the escape of short tobacco is reduced by means of the present invention by distributing the collected short tobacco over the surface of the combing roller 7, so that the recovered short tobacco is carried 15 forwardly by the roller 7, by reason of the fact that the short tobacco is returned to the hopper at the same rate as that at which it falls between the feeding rollers.

Instead of the construction described, the 20 bands 14 and 17 could be arranged to convey the collected short tobacco above and parallel to the axis of the roller 10 so that the shorts could be deposited on the roller 10, or alternatively, the short tobacco could be conveyed into the chute 25 (which could be enlarged for the purpose) to the left of the picker roller 11 as seen in Figure 1, so that the shorts could be deposited on to the travelling surface 12 running along the trough 13 of the cigarette making machine.

30 In both these two last mentioned examples the principle of the relatively inverted L shaped paths of the endless bands can be employed and a spiral sweeping element arranged to remove the tobacco at the desired position. Where the 35 co-operating limbs of the L's are not vertical as in the construction shown in the drawings, the endless belts could pass round suitable conical pulleys or rollers at the junction between the bases and the co-operating portions of the L's, 40 so that the surface on which the tobacco is collected and the surface from which the tobacco is removed can be maintained in horizontal planes.

It will be appreciated that the sweeping element 19 is preferably made in the form of a 45 worm or is of spiral formation in order to facilitate the feeding of the tobacco into the correct position by the supporting surface, but if desired, the sweeping element may comprise a deflecting member which is substantially parallel 50 with the axis of rotation of the member, and in such a case the deflecting member would either comprise a single element such as a blade or a narrow brush or a plurality of elements arranged at spaced intervals around the spindle 21.

55 What is claimed as the invention and desired to secure by Letters Patent is:—

1. In apparatus of the character described, the combination of a conveyor to receive short tobacco, means cooperating with said conveyor to maintain said short tobacco on said conveyor in substantially the same formation in which it was received thereon until it is discharged therefrom, said means also constituting a support movable in timed relation with said conveyor and adapted to receive said short tobacco therefrom and convey said tobacco to a delivery point, and means adjacent said delivery point for removing said tobacco from said support, said last named means comprising a device for sweeping said tobacco laterally from said support.

2. In apparatus of the character described, the combination of a conveyor to receive short tobacco, means cooperating with said conveyor to maintain said short tobacco on said conveyor in substantially the same formation in which it was

received thereon until it is discharged therefrom, said means also constituting a support movable in timed relation with said conveyor and adapted to receive said short tobacco therefrom and convey said tobacco in a predetermined path, and means for discharging downwardly the tobacco thus conveyed so as to distribute the same in a direction parallel to such path.

3. In apparatus of the character described, the combination of an endless band conveyor to receive short tobacco, a second endless band adapted to cooperate with said conveyor to maintain said tobacco thereon, said second endless band also providing a movable support for receiving from said conveyor and conveying said tobacco in a predetermined path, and means for discharging downwardly the tobacco thus conveyed so as to distribute the same in a direction parallel to such path.

4. In apparatus of the character described, an endless band conveyor having a substantially L-shaped path and adapted to receive short tobacco at points along the horizontal portion of said path, a second travelling endless band having substantially an inverted L-shaped path, vertical runs of said conveyor and said second endless band cooperating to hold said tobacco therebetween and a horizontal run of said second endless band being adapted to receive and convey said tobacco from said conveyor in a predetermined path, and means for discharging downwardly the tobacco thus conveyed so as to distribute the same in a direction parallel to such path.

5. Apparatus for use in cigarette tobacco shred feeding machines, wherein short tobacco separates from the fed tobacco during the feeding operation, comprising the combination with a conveyor receiving the separated short tobacco, of means cooperating with said conveyor to maintain said short tobacco on said conveyor in substantially the same formation in which it was received thereon until it is discharged therefrom, said means also constituting a support movable in timed relation with said conveyor and adapted to receive said short tobacco therefrom and convey said short tobacco to a delivery point, and means adjacent said delivery point for distributing the short tobacco upon the longer fed tobacco in the machine.

6. Apparatus for use in cigarette tobacco shred feeding machines, wherein short tobacco separates from the fed tobacco during the feeding operation, comprising the combination with a conveyor receiving the separated short tobacco, of means cooperating with said conveyor to maintain said short tobacco on said conveyor in substantially the same formation in which it was received thereon until it is discharged therefrom, said means also constituting a support movable in timed relation with said conveyor and adapted to receive said short tobacco therefrom and convey said short tobacco to a delivery point, and means adjacent said delivery point for distributing the short tobacco upon the longer fed tobacco in the machine and transversely of the direction of feed of the longer tobacco.

7. Apparatus for use in cigarette tobacco shred feeding machines, wherein short tobacco separates from the fed tobacco during the feeding operation, comprising the combination with an endless band conveyor to receive the separated short tobacco, of a second endless band adapted to cooperate with said conveyor to maintain said short tobacco thereon, said second endless band

also providing a movable support for receiving from said conveyor and conveying said short tobacco to a delivery point, and means adjacent said delivery point for distributing the short tobacco upon the longer fed tobacco in the machine.

8. Apparatus for use in cigarette tobacco shred feeding machines of the type employing a carded conveyor on which a tobacco carpet is formed, and wherein short tobacco is separated out during the formation of such carpet, comprising the combination with a conveyor receiving the separated short tobacco, of means cooperating with said conveyor to maintain said short tobacco on said conveyor in substantially the same formation in which it was received thereon until it is discharged therefrom, said means also constituting a support movable in timed relation with said conveyor and adapted to receive said short tobacco therefrom and convey said short tobacco to a delivery point, and means adjacent said delivery point for distributing the short tobacco upon the said tobacco carpet.

9. Apparatus for use in cigarette tobacco shred feeding machines of the type employing a carded conveyor on which a tobacco carpet is formed, and wherein short tobacco is separated out during the formation of such carpet, comprising the combination with a conveyor receiving the separated short tobacco, of means cooperating with said conveyor to maintain said short tobacco on said conveyor in substantially the same formation in which it was received thereon until it is

discharged therefrom, said means also constituting a support movable in timed relation with said conveyor and adapted to receive said short tobacco therefrom and convey said short tobacco in a predetermined path, and means for discharging downwardly the short tobacco thus conveyed so as to distribute the same on the tobacco carpet transversely of the direction of movement of the carpet.

10. Apparatus for use in cigarette tobacco shred feeding machines, wherein short tobacco separates from the fed tobacco during the feeding operation, comprising the combination with an endless band conveyor having a substantially L-shape path and adapted to receive the separated short tobacco at points along the horizontal portion of said path, of a second travelling endless band having substantially an inverted L-shaped path, vertical runs of said conveyor and said second endless band cooperating to hold said short tobacco therebetween and a horizontal run of said second endless band being adapted to receive and convey said short tobacco from said conveyor to a delivery point, and means adjacent said delivery point for distributing the short tobacco upon the longer fed tobacco in the machine.
